Joseph Vale

United States Patent Office.

JOSEPH VALE, OF BELOIT, WISCONSIN.

Letters Patent No. 79,615, dated July 7, 1868.

IMPROVEMENT IN BAKE-OVENs.

The Schedule referred to in these Letters Patent and making part of the same.

TO ALL WHOM IT MAY CONCERN:

Be it known that I, JOSEPH VALE, of the city of Beloit, Rock county, in the State of Wisconsin, have invented certain new and useful Improvements in Rotary Bake-Ovens; and I do hereby declare the following description and accompanying drawings are sufficient to enable any person skilled in the art or science to which it most nearly appertains to make and use my said invention or improvements without further invention or experiment.

The nature of my invention and improvements consists in providing a rotating oven so greatly simplified in construction and arrangement, as well as so very largely reduced in cost of manufacture, as to be available to the public for general use not only in large establishments, but for hotels, eating-houses, hospitals, boarding-houses, and large farmers and families.

Simplicity of construction and arrangement must recommend it to public favor.

Figure 1 of the drawing is a perspective view of the exterior of the oven.

Figure 2 is a horizontal sectional view, taken in a line through the oven at the top of the fixed hearth.

Figure 3 is a perspective view of the rotating hearth H and shaft H detached.

Figure 4 is a vertical section nearly through the centre from front to rear of the oven.

Similar letters of reference indicate like parts in all the figures.

The walls and fixed hearth of the oven may be constructed of brick or stone, and of any size required to supply the business to be done.

A represents the walls and body of the oven, H the revolving hearth and pivoted shaft, to which it is secured by suitable arms. The revolving hearth is constructed of suitable sheet metal, supported by metallic arms, and the said revolving shaft having a suitable step-box, in which the lower end of said pivot may freely revolve. The said revolving hearth is rotated by inserting the pointed end of a spike or poker into the perforations shown in the turned-down edge, or outer rim of the said revolving hearth H of fig. 3, moving the same with convenient ease.

C C are fire-grates, and the doors opening into the same as shown in figs. 1, 2, and 4.

C, fig. 2, shows one of the fire-grates, having the iron cover removed, for the purpose of exhibiting its position.

D D are doors for regulating the draught of the furnaces, and withdrawing ashes from under the grates.

d d are heavy iron covers for the fire-flues or furnaces, in the drawings, one of which is removed to show the fire-grate C, fig. 2.

a a is the smoke-flue or chimney.

b b are flues for admitting the heated air into the baking-chamber directly under and around the rotating hearth.

g is a sliding damper, by the employment of which smoke and gases are allowed to escape through the flue or chimney a a, and is operated by the hook at g, fig. 2.

The crown E of the oven is made of heavy sheet metal, suitably supported by ribs or arms, which, however, are not shown in the drawings. The upper end of the revolving shaft H is pivoted through the centre of said crown E, and when in use the said oval disk or crown is covered six to twelve inches deep with sand, to prevent the escape of heat from the oven. The furnaces being directly under the fixed hearth, the heat is admitted to the oven directly, circulating under the rotating hearth, ascending by the spaces between the rim of said hearth and the wall of the oven, also up through the opening around the shaft H, pervading every part of the oven at the same time.

The oven is operated, in baking, through the door B, fig. 1. Batches of bread or pastry are placed upon the hearth H successively, until one revolution has been made, when it will be found that those first placed thereon are sufficiently done to be removed to the larder. Unbaked batches take the place of those removed, and this operation may be repeated and continued without intermission the year round—a measure of efficiency almost unbounded.

I am aware that a rotary oven or ovens have already been patented, and therefore do not claim broadly as such; but

What I claim as my invention, and desire to secure by Letters Patent, is—

The rotating disk or hearth H, secured to and turning upon the shaft II, and the mode herein described of rotating the same, whereby expensive gear and pinions are dispensed with.

I also claim the crown-plate or disk E, in combination with the fire-grates C C, covers d d, flues b b, regulating-damper g, flue or chimney a a, and ash-boxes D D, when the whole are constructed and arranged substantially as herein set forth and described, to operate as specified.

JOSEPH VALE.
